DESIGN FOR A BOTTLE

David Trompeter, New York, N. Y.

Application July 13, 1935, Serial No. 57,613

Term of patent 14 years

To all whom it may concern:

Be it known that I, David Trompeter, a citizen of the United States, residing at 1457 Broadway, New York city, in the county of New York and State of New York, have invented a new, original, and ornamental Design for a Bottle, of which the following is a specification, reference being had to the accompanying drawing constituting a part hereof.

I claim:

The ornamental design for a bottle as shown.

In testimony whereof, I have hereunto subscribed my name this 27th day of June, 1935.

DAVID TROMPETER.
